MULTICOLOR MAGAZINE FOR LOOMS

Application filed August 13, 1929. Serial No. 385,596.

This invention relates to improvements in multicolor magazines for looms and it is the general object of the invention to provide a simplified form of control for the transferrer latch.

The usual multicolor magazine has provision for storing several parallel vertical stacks of bobbins each of which is controlled by a vertical slide. When the weft detector indicates weft exhaustion the slide corresponding to the active shuttle is raised, and when the same shuttle is again under the magazine on a later pick the raised slide is depressed. In its downward movement the slide rocks a device which moves the shuttle feeler into shuttle detecting position and also raises the transferrer latch so that the latter is in the path of a bunter on the lay. In previous constructions the latch lifting device has been made in several parts and has included a knuckle joint having in its construction a lever the effect of which is to raise the transferrer latch by an upward movement. It is an important object of my present invention to simplify the aforesaid device and to eliminate the reversing lever so that the latch may be raised by fewer parts.

It is a further object of my present invention to place the knuckle joint in a more convenient position where it may act centrally with respect to the vertical slides, the shelf or portion of the device which cooperates with the slides being divided to make room for the knuckle joint. It is a more specific object of the invention to form the magazine frame so that it will cooperate with the simplified joint so as to limit the latter in both directions and afford a seat for a portion of the joint.

It is a further object of my present invention to place the spring which acts to yieldingly lock the rocking device at a point intermediate the bearings of the latter so that in case of wearing uniform clearance will exist between the shelves of the rocking member and the vertical slides.

With these and other objects in view which will appear as the description proceeds, my invention resides in the combination and

arrangement of parts hereinafter described and set forth in the claims.

In the accompanying drawings wherein a convenient embodiment of my invention is set forth,

55

Fig. 1 is a side elevation taken from the interior of the loom showing the multicolor magazine having my invention applied thereto,

Fig. 2 is a horizontal section looking down along the line 2—2 of Fig. 1,

Fig. 3 is a detailed vertical section on line 3—3 of Fig. 2 showing the knuckle joint in two different positions, and

Fig. 4 is a vertical section on line 4—4 of Fig. 2.

Referring particularly to Fig. 1, I have shown the loom frame 10 supporting a foot 11 of the magazine M. A transferrer lever 12 is pivoted as at 13 to the foot and has a depending arm 14 to which is pivoted a latch carrier 15. The latter may be secured in any approved manner to the holder and is adapted for cooperation with the bunter 17 on the lay L.

A shuttle feeler 18 is pivotally mounted to move about a stud 19 in a vertical direction and is depressed by means of an upright rod 20 whenever transfer is about to take place. When in low position the shuttle feeler detects for the correct boxing of the shuttle S and if the shuttle is misplaced it will raise the feeler and through mechanism to be described will effect lowering of the latch 16 to prevent transfer.

The color slide designated herein as at 21 has longitudinal and angular movements and is proportioned to cooperate with the vertical slides 22, 23, 24 and 25 which extend, respectively, from the front to the rear of the magazine. The color slide is under control of the box motion or pattern mechanism and in this way is able to determine which of the vertical slides shall effect release of the bobbin to be transferred into the depleted shuttle. Each vertical slide has pivoted thereto a dog 27 which in normal position with the slide down is retracted but which projects over structure to be described when the slide is raised.

The matter thus far described is of common construction and forms no part of my present invention. For a more complete understanding of the construction in operation, however, reference may be had to prior patent to Ryon No. 1,030,748.

In carrying my invention into effect I provide improved connections between the rod 20 and the latch 16, said connections including an improved rocking member for cooperation with one or another of the vertical slides. The magazine frame has extended therefrom toward the center of the loom a pair of horizontal arms 30 through which extends a pin or shaft 31 substantially parallel to the color slide 21. A set screw 32 may be employed to hold the shaft in position in the arms. The rocking member 33 has spaced hubs 34 and 35 which lie, respectively, behind and in front of the arms 30. Extending from the hub 34 and lying between the pin 31 and the magazine is a finger 36 operatively connected to the upper end of the rod 20. A short shelf 37 is also cast integral with the finger 36 and is adapted for cooperation with the rear slides 24 and 25.

The front hub 35 in like manner has extending therefrom a somewhat longer finger 38 which is pivotally connected to the upper end of a depending rod 39 the lower end of which is operatively connected as at 40 to the latch holder 15. A second shelf 41 similar to shelf 37 extends from the finger 38 to cooperate with one or another of the vertical slides 22 and 23. The shelves 37 and 41 have upper surfaces 42 to cooperate with the dogs 27 pivotally connected to the vertical slides.

In operation it is necessary that the rocking member move from one to another predetermined angular position, and in order to effect this movement I cast on the rocking member an auxiliary bearing 44 through which the pin 31 extends. This bearing extends toward the magazine and is forked as at 45 to receive a pin 46. A plunger 47 has a reduced end 48 lying between the forked end of the bearing 44 and pivotally connected thereto by the pin 46. A shoulder 49 on the plunger receives the thrust of a compression spring 50 the other end of which bears against a washer 51.

As shown in Fig. 3 the washer is restrained as to movement to the right by means of a web 52 extending between flanges 53 and 54, respectively. These flanges are of the usual form except for the bridge 52 and assist in defining two of the four bobbin compartments C shown. The bridge may have a convex surface 55 over which the washer 51 slides and is perforated as at 56 to permit passage therethrough of the plunger 47. Cast integral with the frame of the magazine and extending above and below the rod 47 are stop lugs 57 and 58, respectively.

These lugs are positioned to engage the auxiliary bearing to limit angular movement of the rocking member.

Under normal conditions the rocking member will be in the position shown in full lines in Fig. 3, the spring 50 holding the bearing against the upper stop lug 57. When a previously lifted vertical slide moves down preparatory to transfer it will engage one or the other of the shelves 37 or 41, rocking the member 33 in a clockwise direction as viewed in Fig. 3 around the pin 31 so that said member and the rod 37 will assume the dotted line position shown in Fig. 3. This movement causes a depression of rod 20 to move the shuttle feeler 18 to a shuttle feeling position and also causes a lowering of rod 39 which effects lifting of the rear or left hand end of the latch 16 as viewed in Fig. 1 into the path of the bunter 17. During the latter part of the forward movement of the lay the shuttle feeler will be moved upwardly by the box back B, thereby restoring the rocking member to its normal position.

From the foregoing it will be seen that I have provided a very simple construction wherein the shelves 37 and 41 are spaced to provide room for the knuckle joint, thereby using space which has heretofore been unused in magazines of the multicolor type. It will further be seen that the spring 50 bears against a small web which extends between the flanges 53 and 54 and it will also be noted that the stop lugs above and below the knuckle joint are of simple form and effectively limit angular movement of the rocking member. The action of the spring 50 is distributed equally between the hubs 34 and 35 and any wearing which may result in the turning of the member 33 on the pin 31 will be uniform, the spring holding the shelves at equally spaced distances from their corresponding vertical slides. It will also be seen that the construction is such that a single set screw 32 is sufficient to hold all the devices in proper longitudinal position. Furthermore, it will be noted that the reversing lever of previous constructions has been eliminated, the control of the latch being more direct in the present instance.

Having thus described my invention it will be seen that changes and modifications may be made therein by those skilled in the art without departing from the spirit and scope of the invention and I do not wish to be limited to the details herein disclosed, but what I claim is:

1. In a weft replenishing mechanism including a magazine having vertical slides and shuttle feeler and transfrerer latch elements to be controlled by the slides, a rocking member operatively connected to the said elements, a pair of spaced bearings between certain of the vertical slides, pivotal connections between the bearings and the rocking mem-

ber, a spring actuated knuckle joint between the magazine and the rocking member to hold the member yieldingly in either of two positions, said joint being between the bearings, and two spaced shelves lying outside the bearings to cooperate with the vertical slides to move the member against the action of the spring actuated joint.

2. In a weft replenishing mechanism having vertical slides and shuttle feeler and transerrer latch elements to be controlled by the slides, a rocking member operatively connected to the said elements, a pair of spaced bearings between certain of the vertical slides, pivotal connections between the bearings and the rocking member, a pair of fingers extending in opposite directions from the member and both lying between the slides and the axis of the pivotal connection, shelves integral with and extending from the fingers, one for each finger, to cooperate with the vertical slides, the shelves lying between the fingers and slides, and means to yieldingly lock the rocking member in two different positions.

3. In a weft replenishing mechanism having vertical slides and shuttle feeler and transerrer latch elements to be controlled by the slides, a rocking member operatively connected to the said elements, a pair of spaced bearings between certain of the vertical slides, pivotal connections between the bearings and the rocking member, a pair of fingers extending in opposite directions from the member and both lying between the slides and the axis of the pivotal connections, shelves extending from the fingers, one for each finger, to cooperate with the vertical slides, the shelves lying between the fingers and slides, and means to yieldingly lock the rocking member in two different positions, said means including a spring pressed part located between the bearings.

4. In a weft replenishing mechanism having two spaced groups of vertical control slides and shuttle feeler and transerrer latch elements to be controlled by the slides, a pair of spaced bearing members extending from the replenishing mechanism between the groups of slides, a rocking device operatively connected to the elements, a pivotal connection between the bearings and the rocking device, a pair of shelves rigid with the device, one shelf for each group of slides, said shelves being outside the bearings and positioned to be operatively related to slides, and means between the bearing members and shelves to yieldingly resist rocking of the device against the action of the slides.

5. In a weft replenishing mechanism having two spaced groups of vertical control slides and shuttle feeler and transerrer latch elements to be controlled by the slides, a pair of spaced bearing members extending from the replenishing mechanism between the

groups of slides, a bearing pin supported by the bearing members, a rocking device supported by the pin, said device having integral therewith a pair of oppositely spaced fingers, one for each element, said fingers lying outside the bearing members, a shelf integral with each finger, one shelf for each group of slides, the fingers and shelves lying between the bearing members and shelves to yieldingly resist rocking of the device against the action of the slides.

6. In a weft replenishing mechanism having two spaced groups of vertical control slides and shuttle feeler and transerrer latch elements to be controlled by the slides, a pair of spaced bearing members extending from the replenishing mechanism between the groups of slides, a bearing pin extending through and beyond the bearing members and held fixed to the bearing members, a rocking device having spaced hubs outside the bearing members and pivotally mounted on the pin, a finger integral with each hub, the fingers extending in opposite directions, one for each element, a shelf integral with each finger, one shelf for each group of slides, the fingers and shelves lying outside the bearing members and between the pin and vertical slides, an additional pivotal connection between the pin and device integral with the latter and lying between the bearing members and extending to a point between the pin and slides, and a yielding means interposed between the additional pivotal connection and the replenishing mechanism to resist rocking of the device under action of the slides, said yielding means lying between the bearing members.

In testimony whereof I have hereunto affixed my signature.

WILLIAM M. WATTIE.
